UNITED STATES PATENT OFFICE.

ROBERT KELSO, OF PHILADELPHIA, PENNSYLVANIA.

WOVEN-WIRE BUSTLE.

SPECIFICATION forming part of Letters Patent No. 323,692, dated August 4, 1885.

Application filed April 28, 1885. (No model.)

To all whom it may concern:

Be it known that I, ROBERT KELSO, of Philadelphia, in the county of Philadelphia and State of Pennsylvania, have invented a new and valuable Improvement in Woven-Wire Spring-Bustles; and I do hereby declare that the following is a full, clear, and exact description of the construction and operation of the same, reference being had to the annexed drawings, making part of this specification, and to the letters and figures of reference marked thereon.

Figure 1 is a perspective representing a bustle having a body or web of interwoven spiral-spring coils embodying my invention. Fig. 2 is a front elevation of same, and Fig. 3 is a broken perspective of detail part of same.

My invention has relation to bustles or skirt supporters; and it has for its object to provide a bustle of extreme flexibility and elasticity which presses out flat in sitting down, reclining, or when otherwise subjected to pressure by the wearer, and which when such pressure is relieved returns to its original or normal shape.

My invention accordingly consists of a bustle made of interwoven spiral-spring coils, supporting and fastening tapes, and strengthening side bands, as hereinafter more particularly described and claimed.

In the drawings, A represents a bustle, the body or web of which is made of spiral-spring coils interwoven into and connected in a manner similar to the formation of the well-known woven-wire mattress, or is made up of interwoven spiral-spring coils, the same being made in one entire web or sections of webbing. The coils may run longitudinally, transversely, or diagonally, or any combination of same may be employed. The upper, lower, and some of the intermediate coils, a' , a'' , and a''' , respectively, of the web are preferably composed of a number of strands or wires to give an extra degree of stiffness, strength, and elasticity to said coils, or they are stiffer than the remaining coils of the web or body a . The sides a^4 of web a are preferably inserted in an

oblong sheet or other socket, b , and clamped therein by pressing the sides of the sockets together to grip upon said ends or sides of the 50 spiral coils of web a , as plainly illustrated in Fig. 3. These sockets b are preferably covered by or inclosed in tapes or bands c , the upper ends of which are sewed to the waist band or tape d , which has a buckle, d' . The 55 tapes c or socket sides b of web a are in front connected by an adjustable tape, e , for supporting the lower part of the bustle in position upon and causing it to project from the body of the wearer.

The upper edge, a' , of web a is connected at intervals to the waistband d by loops f , which are sewed to said band, as shown, all of said parts forming a durable and extremely elastic bustle, which flattens out when subjected to pressure, and instantly assumes its normal shape when such pressure are relieved.

If additional elasticity and firmness are desired for the web a , heavy or stiffened coils a^5 may be vertically woven into the web.

I am aware that webs or bodies for bustles have been made of rolls or coils of wire braided together; but as these coils are not spring-coils, and are not interwoven into one another, a web so formed is not made in accordance 75 with my invention, and I therefore disclaim the same.

What I claim is—

1. A bustle made of interwoven spiral-spring coils, and having waistband d , loops f , 80 tapes c , and supporting-tape e , substantially as shown and described.

2. A bustle made of interwoven spiral-spring coils having stiffened upper and lower edges, a' a'' , and like cross or transverse coils 85 a^5 , substantially as shown and described.

In testimony that I claim the above I have hereunto subscribed my name in the presence of two witnesses.

ROBERT KELSO.
